(57) **CLAIM**

The ornamental design of a face milling cutter having peripherally spaced inserts and inner deburring inserts, as shown and described.

DESCRIPTION

FIG. 1 is a perspective view of a face milling cutter having peripherally spaced inserts and inner deburring inserts showing my new design;

FIG. 2 is a front view thereof;

FIG. 3 is an end view thereof, the opposite end view being a mirror image;

FIG. 4 is a rear view thereof;

FIG. 5 is a side view thereof; and,

FIG. 6 is an opposite side view thereof.
